UNITED STATES PATENT OFFICE.

ASAHEL A. PORTER, OF NAUGATUCK, CONNECTICUT.

CURRENT WATER-WHEEL.

No. 873,082.

Specification of Letters Patent.

Patented Dec. 10, 1907.

Application filed July 22, 1903. Serial No. 166,586.

To all whom it may concern:

Be it known that I, ASAHEL A. PORTER, a citizen of the United States, and a resident of Naugatuck, in the county of New Haven and State of Connecticut, have invented a new and Improved Current Water-Wheel, of which the following is a full, clear, and exact description.

The object of the invention is to provide a new and improved current water wheel, which is simple and durable in construction, very effective in operation, and arranged to revolve in either direction, without change in the direction of the current or the location 15 of the wheel in the current, and to allow of using the wheel in either a vertical or a horizontal position.

The invention consists of novel features and parts and combinations of the same, as 20 will be more fully described hereinafter and then pointed out in the claims.

A practical embodiment of the invention is represented in the accompanying drawings forming a part of this specification, in which 25 similar characters of reference indicate corresponding parts in both views.

Figure 1 is a plan view of the improvement; and Fig. 2 is an enlarged elevation of the wheel and its frame.

30 The flume A in which the wheel B is arranged, is provided in its sides with vertically disposed guideways C, for the sides of the wheel frame D to slide in, and on the top of the said frame sides are secured chains E 35 or the like, connected with a windlass or other suitable hoisting apparatus, for suspending the wheel B the desired distance in the water flowing through the flume A, the level of the water being preferably a distance above the top of the wheel, so that the 40 latter is completely immersed in the water.

The wheel B is provided with spaced circular heads B' and B'', secured on a shaft B³, connected by a gear wheel F or other means 45 with the machinery to be driven, and between the said heads B' and B'' are arranged wings B⁴, mounted to swing from pivots B⁵ arranged in the heads B' and B'', the said pivots B⁵ being located near the rims of 50 the heads, and the free ends of the wings B⁴ are adapted to come against either of the adjacent stops B⁶, secured to the heads B' and B''. Now the wings B⁴ are pivoted on a radial line 55 midway between the stops B⁶, that each wing may engage a stop when swinging either direction from one side to the other, so that

when the current is directed towards one side of the wheel, the wings abut against their stops B⁶, so that the force of the water on the wings rotates the wheel B, say in the direction of the arrow a', and when the wings reach the lower end of the wheel, they readily swing into an open position, that is, parallel to the current, so as to give as little resistance to the water as possible during the return movement, as will be readily understood by reference to Fig. 1. It is understood that the current is directed to either side of the wheel B, to rotate the latter, and when directed to the left hand side, the wheel is rotated in the direction indicated by the arrow a' in Fig. 1; but when the current is directed to the right hand side of the wheel B, then the wheel B is reversed, that is, it rotates in the inverse direction of the arrow a' and the wings B⁴ close while passing to the right hand side of the wheel, and open during their return travel on the left hand side of the wheel.

Now in order to direct the current to either side of the wheel, a plurality of gates G, G', G² and G³ are provided, having vertically disposed shafts G⁴ journaled in suitable bearings in a gate frame H, fitted in vertical guideways C' arranged on the sides of the flume A. On the upper ends of the shafts G⁴ are secured 80 hand wheels I, under the control of the operator, to turn the gates G, G', G² and G³ into the desired position, so as to direct the water to either side of the current wheel B, and on the upper ends of the shafts G⁴ are also secured 85 notched segments J, adapted to be engaged by locking catches K, fulcrumed on the frame H and serving to hold the notched segments J and consequently the shafts G⁴ and the gates G, G', G² and G³ in the desired 90 position.

Now as indicated in Fig. 1, the gate G³ is in a closed position, to direct the water from the right hand side of the flume A towards the middle thereof, for the water to act on the 100 closed wings B⁴, so as to turn the wheel B in the direction of the arrow a'. In a like manner the gates G², G' and G are set, to properly direct the current in the remaining portion of the flume, so that the water effectively acts 105 on the closed wings B⁴, to insure a full utilization of the power of the current.

The wheel may be stopped by moving the forward extremities of the gates G and G³ inwardly until they substantially touch each 110 other; if necessary, the gates G' and G² may be brought together in a similar manner; in

this way, the current flowing through the flume would be substantially shut off and the wheel would soon come to a stop.

In order to reverse the direction of rotation 5 of the wheel, the operation just described would be gone through with.

Although I have shown the wheel B arranged in a flume, this is not absolutely necessary, as the water wheel may be readily 10 disposed in a river or other current, without the use of a flume, and if desired the wheel may be disposed horizontally in the current instead of vertically, but in either case approximately one-half of the wings are in a 15 closed position for doing work, while the remaining wings swing freely open, so as to give no resistance to the water.

It will also be seen that the wheel B can be used as an overshot or undershot wheel, or 20 the upper portion can be used as an overshot wheel while the lower portion is simultaneously used as an undershot wheel. By having the wings open, as described, the back pressure is reduced to a minimum, and the 25 wheel can be used either wholly or only partly submerged.

In order to render the gates very effective, the gate frame H carrying the gates is raised

or lowered by suitable mechanism, not shown, 30 the same as the wheel frame D, to bring the gates on the same level with the wheel B.

I do not limit myself to the number of gates shown, or the locking devices for the gates, as the same may be varied without 35 deviating from my invention.

Having thus described my invention, I claim as new and desire to secure by Letters Patent:

In a current water wheel, the combination 40 with a flume, of a vertically slidable frame in the flume, a wheel mounted in the frame and provided with wings pivoted to swing into reverse position and with stops for the wings, a second frame mounted to slide vertically in the flume in front of the wheel frame, a plurality of gates mounted in the second frame, and means for locking the gates in position, 45 as set forth.

In testimony whereof I have signed my name to this specification in the presence of 50 two subscribing witnesses.

ASAHEL A. PORTER.
